[57] CLAIM

The ornamental design for a combination pizza slicer and server, as shown and described.

DESCRIPTION

FIG. 1 is a perspective view of a combination pizza slicer and server, showing my new design;

FIG. 2 is a right side elevation view thereof, showing the serving portion in an extended position;

FIG. 3 is a partial right side elevational view thereof, showing the serving portion in a retracted position;

FIG. 4 is a left side elevation view thereof, showing the serving portion in the extended position;

FIG. 5 is a partial left side elevational view thereof, showing the serving portion in the retracted position;

FIG. 6 is a top plan view thereof;

FIG. 7 is a bottom plan view thereof;

FIG. 8 is a front elevational view thereof; and,

FIG. 9 is a rear elevational view thereof.
